UNITED STATES PATENT OFFICE.

ADNEY T. ARNOLD AND FRANCIS F. EMORY, OF FITCHBURG, MASS.

PISTON-HEAD FOR STEAM-ENGINES.

SPECIFICATION forming part of Letters Patent No. 309,918, dated December 30, 1884.

Application filed July 14, 1884. (No model.)

To all whom it may concern:

Be it known that we, ADNEY T. ARNOLD and FRANCIS F. EMORY, both of Fitchburg, in the county of Worcester and Commonwealth of Massachusetts, have invented certain new and useful Improvements in Adjustable Piston-Heads for Steam-Engines; and we do hereby declare the following to be a full, clear, and exact description of the same, reference being had to the accompanying drawings, forming a part of this specification, in which—

Figure 1 represents an end view of a piston-head with our improvement applied thereto. Fig. 2 represents a central section on line A 15 B, Fig. 1; and Fig. 3 represents a section on line C D, Fig. 2.

The nature of our invention consists in the combination of the piston-head with the piston-rod, whereby the piston-head can be adjusted bodily up or down independently of the piston-rod to which it is attached, as will be hereinafter more fully described.

To enable those skilled in the art to which our invention belongs to make and use the same, we will proceed to describe it more in detail.

In the drawings, the part marked E represents a section of a piston-rod the end E' of which is made tapering or in conical form 30 from the point a to the point b, while from the shoulder b projects a bolt part, F, with a screw-thread cut thereon to receive the fastening-nut F'.

G is a spider, which, with its attached parts, 35 forms the piston-head, and which spider is provided with a rim, G', and a central projecting part, H. To the outer end of the spider is secured a circular plate or cap-piece, I, provided with a circular shoulder, d, which fits 40 inside the flange G', and is held in place by means of screw-bolts e, whose heads enter recesses in the cap-piece I, so that when they are screwed up firmly into position their heads will be inside the face of the cap-piece I, the 45 screw parts of bolts e entering screw-holes formed in the projecting part H, as fully indicated in full and dotted lines in the drawings. A hole, f, is cut in the inner side of the spider G, of sufficient size to allow the spider to slip 50 over the largest part of the conical end of the

piston-rod, whereby said spider can be removed and replaced, as desired. A rectangular opening, J, is formed in the projecting part H, through which the conical part of the piston-rod projects, and within this rectangular opening are fitted two saddles, K K. The inner faces of these saddles are curved and inclined or tapered to correspond to the tapering or conical part of the piston-rod, as fully indicated in Fig. 2 of the drawings; and after 55 these saddles are slipped into place set screws or bolts g are inserted through the sides of projection H, at right angles to the piston-rod, and screwed down upon the saddles K, as more fully indicated in Fig. 2 of the drawings, 60 thereby holding the piston-head securely in its adjusted position. Check-nuts h are employed upon the bolts g to keep them from working loose. The back side of the spider or piston-head G is grooved out, as shown at 65 i, to receive one side of the collar L, which is forged upon or otherwise permanently and securely fastened to the piston-rod, and against which collar the spider or piston-head G is forced and clamped when holding-nut F' is 70 screwed or turned into position, as indicated in Fig. 2 of the drawings.

In fitting the spider or piston-head G to receive the respective parts used in combination therewith holes are drilled through the flange 80 G' and thence into the projection H, to receive said bolts g. After such holes have been drilled and tapped out in the projection H the holes in the flange G' can be plugged up, thereby making the head steam and water 85 tight.

Packing-rings m, of any of the usual forms, 90 may be employed in the grooves in the outer face of the piston-head G and cap I, as indicated in Fig. 2.

From the foregoing description it will be seen that if the piston-head or the bottom of the cylinder wears, by simply removing cap I and loosening bolts or set-screws g and holding-nut F', the piston-head can be raised or 95 lowered, thereby readjusting it independently of the piston-rod, which is left in its normal position in the center of the cylinder, thereby overcoming the objections to the forms of construction in use prior to our invention. 100

It will be observed by those skilled in the art to which our invention belongs that the conical end of the piston-rod is so securely clamped and held by the saddles K that the 5 piston-head cannot move out of place, even though holding-nut F' should be loosened. Then, again, by the use of our invention there is no danger of the cylinder ever becoming shouldered, since the piston-head can always 10 be adjusted independently of the piston-rod and can be run out over the counterbore of the cylinder at each extreme end of its stroke.

If preferred, the projecting part H may be made so as to contain three or more saddles, 15 with accompanying screws or bolts g, said saddles being arranged, of course, at equal distances apart, although we prefer the arrangement shown in the drawings.

Having described our improvements in adjustable piston-heads, what we claim as new, 20 and desire to secure by Letters Patent, is—

1. The combination, with a tapering or conical piston-rod provided with a fixed collar, of two or more tapering saddles provided with adjusting bolts or set-screws for adjusting the 25 piston-head relatively to the piston-rod, substantially as described.

2. The combination, with the piston-rod E, provided with a conical or tapering end, E', of spider or piston-head G, provided with the 30 projection H, cap I, holding-nut F', saddles K, and bolts or set-screws g, substantially as and for the purposes set forth.

ADNEY T. ARNOLD.
FRANCIS F. EMORY.
